BY

ATTORNEY

UNITED STATES PATENT OFFICE.

ALBERT COOK HALL, OF DENVER, COLORADO.

WAGON-WHEEL.

SPECIFICATION forming part of Letters Patent No. 353,744, dated December 7, 1886.

Application filed August 21, 1886. Serial No. 211,457. (No model.)

To all whom it may concern:

Be it known that I, ALBERT COOK HALL, of Denver, in the county of Arapahoe and State of Colorado, have invented a new and Improved Wagon-Wheel, of which the following is a full, clear, and exact description.

Reference is had to the accompanying drawings, forming a part of this specification, in which similar letters of reference indicate corresponding parts in all the figures.

Figure 1 is a partial side elevation of my improved wagon-wheel. Fig. 2 is a diametrical section. Fig. 3 is a partial plan view. Fig. 4 is a longitudinal section of one of the spokes. Fig. 5 shows three views of the felly F. E³ is a section of the form it is rolled. F is a section of the form it is made to assume and the form used on the wheel. E' is a plan of felly, and shows the lugs E⁴, which occur on the felly only where the spokes join it.

The objects of my invention are, first, to provide a light, durable, and strong wagon-wheel entirely of metal; second, to provide a wheel in which the tendency to crystallize is reduced to a minimum; third, to provide a wheel on which the tire is independent of the mechanism of the felly and spokes, and on which new tires can be placed at any time.

My invention consists in the combination, with a metallic hub and spokes clamped together, of a metallic felly formed in the shape of the letter U, secured by rivets around the outer ends of spokes, all as hereinafter fully described. Said hub consists of the box H, having a shoulder formed on the inner end and a thread and nut on the outer end. Surrounding this box are three collars, D, C, and B. D bears against the shoulder of the box H. A nut, I, on the outer end of the box bears against the collar B. They are thereby clamped together. These collars being clamped tightly together, holes are drilled through at a slight angle, said holes being a trifle smaller than the tenons A' of the metallic spokes A, of which Fig. 4 is a section. When the spokes are put in place, the collars are separated, the spokes placed between them. The holes in the collars then clasp the tenons of the spokes very tightly before the collars come together.

The metallic spokes A are made of metallic

tubing. They are contracted near their ends, forming tenons A' and A', Fig. 4. These tenons may be rolled or stamped in the hot metal.

The metallic felly F is U-shaped in form, and is made as illustrated in Fig. 5. The lugs E⁴ are placed exactly opposite each other, but do not meet. A hole is drilled through them at a slight angle, the size of the tenons on the spokes. A hole is also drilled through the bottom of the felly the size of the spoke. When the spokes are to be put in place, the felly is sprung apart enough to allow the large end of the spoke to pass through the small hole in the lugs. The felly is then brought back to its correct form, and two rivets, G, 65 (shown in the elevation, Fig. 1, and partial plan, Fig. 3,) are placed one on each side of the lugs and riveted while hot. This forces the lugs of the felly tightly around the tenons of the spokes. The wheel is then placed in a lathe-chuck, and the ends of the spokes passing through the collars are turned to fit tightly on the box H. The periphery of the felly and the extremities of the spokes are also turned round and even. A tire can then be placed 75 on the wheel in the usual manner.

The hub ends of the spokes are arranged in alternation near the inner and outer ends of the hub to brace the wheel laterally and increase its strength.

The hub H and collars have been patented, and I am at present an owner in the patent. During extensive experiments made by myself with metallic wheels this hub was used and gave perfect satisfaction. The spokes experienced were solid and of different cross-section, and were connected to the tire by being screwed into it after passing through a wooden felly. The end of the spoke passing through the collars had a head formed on it. This head was made to bear against the under side of the collars by being screwed into the tire. These wheels would rattle very badly, and the spokes would crystallize in a few days.

It is believed that the metallic tube and felly in combination with this hub, all arranged as shown and described in this specification, will obviate these difficulties.

Having thus described my invention, I claim as new and desire to secure by Letters Patent— 100

1. The metallic tubular spokes A, having contracted circular tenons A' near each end, substantially as herein set forth and described.
2. The metallic felly F, U-shaped in cross-section, having inwardly-projecting lugs, as E', placed at equal distances apart upon its circumference, said lugs having grooves fitting the tenons of the spokes and made to securely clamp these tenons by means of rivets 10 passing through the sides of the felly upon each side of the spokes.
3. The combination of the metallic tubular spokes A, having tenons formed near each end, with the metallic felly F, having inwardly-projecting lugs with holes passing through them, and having rivets, one on each side, substantially as herein set forth.
4. In a metallic wheel, the combination of the box H, having a shoulder on its inner end and a screw-thread and nut on its outer end, 20 the collars B, C, and D, clamped between the shoulder and nut and made with grooves upon their edges, forming holes of a size to fit the tenons formed near the inner ends of the spokes A, and the felly F, having inwardly-projecting 25 lugs arranged to secure the outer ends of the spokes.

ALBERT COOK HALL.
